CLAIM

The ornamental design for a rotating horsehead for oilfield pump, as shown and described.

DESCRIPTION

FIG. 1 is an elevational view of one side of a rotating horsehead for oilfield pump showing my new design, the opposite side being a mirror image thereof;

FIG. 2 is a rear elevational view;

FIG. 3 is a front elevational view;

FIG. 4 is a top plan view; and,

FIG. 5 is a bottom plan view.
